HATCH COVER

Harold J. Meek, Staten Island, N.Y., assignor to Jaroco Engineering Co., Hoboken, N.J., a corporation of New Jersey

Filed Mar. 26, 1958, Ser. No. 724,079

13 Claims. (Cl. 114—202)

The present invention relates to a multi-sectioned steel cover for ship's hatches and more particularly to a multi-sectioned hatch cover adapted to be moved in unison to one end of the hatch and stored in horizontal position clear of the hatch opening.

Originally a ship's cargo hatch was covered by laying planks across the opening and lashing a tarpaulin over the planks to make the cover watertight. On a large hatch, considerable time and labor may be required to remove and replace this type of cover. Because of the high cost of maintaining fast schedules, various devices have been proposed to cut down on the time required for opening and closing such hatch openings.

Several types of folding covers have been proposed and are now in use, generally consisting of hinged sections hinged to the hatch coaming. These covers generally fold vertically at the side of the hatch and are opened and closed with the aid of the ship's hoisting gear. Although these covers save a considerable amount of time, there are many problems connected with their usage. Most important, the hatch cover when open, occupies a large area of deck space and generally is in the way when the hatches are being loaded with cargo.

It is an object of the present invention to provide an improved hatch cover for a ship that stores in horizontal position at one end of the hatch opening below the height of the coaming.

Another object of the present invention is to provide an improved multi-sectioned hatch cover that can be quickly moved from a closed watertight position over the hatch opening to an open position at one end of the hatch clear of the hatch opening without the aid of the ship's hoisting gear.

A still further object of the present invention is to provide a hydraulically actuated multi-sectioned hatch cover that can be quickly moved from a closed position covering the hatch opening to an open horizontal position at one end of the hatch clear of the hatch opening.

Another object of this invention is to provide an interconnected multi-sectioned hatch cover employing very simple actuating means and requiring a stowage space of particularly small dimensions.

Fig. 1 shows diagrammatically in an elevational view partly in section, a ship's hatchway equipped with the hatch-cover arrangement of the present invention, the sections being shown in their closed position;

Fig. 2 is a similar view showing the end section in process of moving to the stowed position;

Fig. 3 is a similar view showing the hatch-cover arrangement in the stowed position;

Fig. 4 is a sectional view taken along the line 4—4 of Fig. 1;

Fig. 5 is a sectional view taken along the line 5—5 of Fig. 1;

Fig. 6 is a detail view showing a corner of one of the hatch cover sections;

Fig. 7 is a sectional view taken along the line 7—7 of Fig. 3; and

2

Fig. 8 is a plan view with the cover in the stowed condition.

Referring to the drawings, the coaming 10 is shown to be upstanding from the deck 12. Located inwardly 5 of the coaming 10 within the hatch opening on each side of the hatch is a track 14 on which the wheels of the hatch cover to be described are adapted to travel. At one end of the hatch opening is located a hatch cover storage compartment 16 which is located on the deck 12; 10 and is enclosed by three side walls 18 and a roof 20 which is located at approximately the same height as the upper end of the coaming 10. Between the roof 20 of the storage compartment 16 and the end coaming wall 21 is an opening 22 extending across the width of the hatch 15 and large enough for each section of the hatch cover to pass through in traveling from the coaming into the storage compartment when the hatch is being uncovered.

A hatch cover including a plurality of sections 24, 26, 20 28 and 30 are shown in the closed position in Fig. 1 covering the hatch opening. Section 24 is linked to a section 26 by a link bar 32 which is attached at one end to a slidable gudgeon 34 which is fitted in a slot 36 in the end plates of section 24. The slot 36 extends along a portion of the length of section 24 toward the forward end thereof. The other end of link bar 32 is attached to a slidable gudgeon 38 which is fitted in slot 40 in the end plates of section 26. The slot 40 extends along a portion of the length of section 26 toward the rear end thereof. In referring to the rear end of a section, that end is referred to which is nearest to the storage compartment 16 when the hatch cover is closed.

Section 26 is linked to section 28 by a link-bar 42 which is attached at one end to a slidable gudgeon 44 which is fitted in a slot 46 in the end plates of section 26. 25 The slot extends along a portion of the length of section 26 toward the forward end thereof. The other end of link bar 42 is attached to slidable gudgeon 48 fitted in slot 50 in the end plates of section 28. Slot 50 extends along a portion of the length of section 28 toward the rear end thereof.

Section 28 is likewise linked to section 30 by a link-bar 52 which is attached at one end to a slidable gudgeon 54 which is fitted in a slot 56 in the end plates of section 28. The slot extends along a portion of the length of section 28 toward the forward end thereof. The other end of link-bar 52 is attached to slidable gudgeon 58 fitted in slot 60 in the end plates of section 30. Slot 60 extends along a portion of the length of section 30 toward the rear end thereof.

Thus it can be seen that each section is linked to each adjacent section from the forward part of the forward section to the rear part of the rear section. The sections 24 and 30 thus require only one slot therein since these sections are each only attached to one adjacent section. 50 The sections 26 and 28, however, require two slots therein since these sections are each attached to two adjacent sections, one located forwardly thereof and the other rearwardly thereof.

Section 24 is provided with a pair of T slots 62 extending along the length thereof in its upper surface. The slots 60 62 are adapted to engage a pair of T bars 64, which, as shown in Fig. 7, are attached to the lower surface of the roof 20 of the storage compartment. The forward end 65 of the T bars 64 are wedge shaped for a purpose to be described hereafter. Thus, when the section 24 is removed from the hatch opening, T bars 64 will engage the T slots 62 of the cover section 24 so that the cover section 24 will stow in a horizontal position parallel to the roof 20. A stop member 66 is located at the rear end of each T bar 64 to limit the travel of section 24 to the extent 65 shown in Fig. 3.

The forward end of cover section 24 is attached by a

pair of extension bars 68 to a pair of endless link-belt drag chains 70 which pass over sprocket wheels 72 at the forward end of the hatch and sprocket wheels 74 at the rear end of the hatch. It should be noted that the chains and sprocket wheels are located inside the hatch opening adjacent to the tracks 14 on each side of the hatch. The sprocket wheels 74 are actuated by a hydraulic motor 76, through a gear reducer 78. The sprocket wheels may be rotated in either direction by a control valve 80.

Cover section 24 is provided with a pair of wheels 82 near its forward end and a pair of wheels 84 near its rear end. The wheels are supported at each side of the cover located inwardly of the end plates of the cover sections for engagement with the track. On the rear surface of section 24 is a gasket member 86 extending across the entire width of the section near the upper surface thereof. This gasket member 86 is adapted to engage the front surface of adjoining section 26 when the covers are closed as shown in Fig. 1 to effect a seal across the width of the joint between adjacent cover sections.

Cover section 26 is likewise provided with a pair of wheels 88 at its forward end, a pair of wheels 90 at its rear end, and a gasket member 92 extending across the entire width of the section near the upper end of the end plate thereof. Cover section 28 is also provided with two pairs of wheels 94 and 96 and a rear gasket member 98, all similarly located. Cover section 30 is provided with a forward pair of wheels 100 suspended in the same manner as the remaining wheels by a pair of depending members 102 depending from the upper surface of the section between which members the wheel is mounted on an axle 104 passing through the members and the wheel, as best shown in Fig. 7. At the rear end of rearmost section 30 is located a pair of wheels 106 each of which is supported by a depending bracket 108. The bracket 108 is so arranged that the wheels 106 are located in a lower plane than the wheels 100 and the wheels on the other sections, so that the section 30 when its wheels are resting on the track 14 is at an acute angle with respect to the remaining sections as best shown in Fig. 1.

Extending about the periphery of the upper portion of the coaming is an inflatable sealing gasket 110 which is fitted in a groove 112 at the upper end of the hatch coaming just below the coaming cap 113. When the gasket 110 is inflated, it contacts the cover sections and forms a good seal around the periphery between the coaming and the hatch cover. Further, the inflated gasket 110 compresses the cover sections together against the sealing gaskets 86, 92 and 98 to form lateral seals between each adjacent hatch cover. When in the closed position the hatch cover section 30 completely encloses the opening 22 between the storage compartment 16 and the end coaming wall 21.

The horizontal tracks 14 extend the entire length of the hatch opening and at the inner end of the hatch where the covers are stowed, beginning at the opening 22, the tracks each are curved downwardly in the form of a cam surface 114. The cam surfaces 114 on which the wheels travel are adapted to guide the individual cover sections from the horizontal position on the track 14 to the stowed position as shown in Fig. 3. The cam surface 114 begins to curve downwardly in a sharp nearly 90° curve at a point directly over the sprocket wheel 74.

Extending across the opening 22 immediately over the sprocket wheel 74 is a shaft 116 carrying a plurality of rotatable rollers 118 thereon properly spaced across the width of the hatch opening. These rollers are used to support the hatch sections as they are pivoted into the opening 22 after their rear wheels leave the track 14.

The operation of the apparatus will now be described. Starting with the hatch cover sections in the closed and sealed position shown in Fig. 1, the inflatable gaskets 110 are first deflated to break the seal between the coaming and the cover sections. The control valve 80 is next manipulated to permit flow of hydraulic fluid to the motor

76 to effect rotation of the sprocket wheels 72 and 74 in the proper direction. Rotation of the sprocket wheels results in movement of the endless chains 70, and through extension bars 68, the movement of the cover sections.

5 The cover sections travel toward the storage compartment 16 with their wheels traveling along the track 14. When the rear wheels 106 of section 30 reach the cam surface 114, continued movement of the section 30 causes the wheels 106 to drop off of the track 14 and the bottom of the section engages the rollers 118. The section continues to travel on the rollers 118 and its front wheels 100 until the upper surface of the section 30 engages the wedge-shaped end 65 of the T bars 64. The section 30 is thus tipped downwardly by the wedge-shaped T bars about the rollers 118 until the rear wheels 106 drop into engagement with the cam surface 114, all as shown in the dotted lines in Fig. 2 marked A, B, C and D until the section reaches the fully stowed horizontal position E as shown in Fig. 3.

10 20 As the forward end of the cover section 30 pivots upwardly and travels downwardly on the rollers 118, the link bars 52 control the movement of section 30 preventing a sudden drop of the section. The section 30 thus can be seen to travel through the opening 22 between the roof 25 20 of the storage compartment 16 and the end coaming wall. When in its closed position, the section 30 acts to seal off the opening 22. When the inflatable gasket is deflated, however, and the section moves a slight amount, the wheels 106 drop almost vertically from the track 30 14 thus lowering the rear end of the section 30 and permitting it to pass through the opening 22.

Successive cover sections 28 and 26 pivot similarly guided by the wedge-shaped T bars and pass through the opening 22 into the storage compartment 16. The link 35 bars between the sections are free to float in the slots and act to control the descent of the sections. The rear wheels of each successive cover ride along the top surface of the next lower section into a vertically stacked arrangement of horizontally extending sections.

40 The last section 24 upon reaching the opening 22 will also come into contact with the wedge-shaped ends of the T bars, however, due to the T slots 62 in its upper surface, the T bars will enter the T slots as the cover section travels horizontally through the opening 22 into the storage compartment. When the stop members 66 are engaged by the section 24, as shown in Fig. 3, the section 24 is completely removed from the coaming, and is stored in a horizontally suspended position with the extension bars 68 thereon located directly over the sprocket wheel 74.

45 It can thus be seen that in the fully stowed position, shown in Fig. 3, the hatch cover sections are completely removed from the hatch opening and are stowed in a stacked horizontal arrangement in the storage compartment 16 on the deck below the height of the upper end of the coaming. The roof 20 of the storage compartment is flat and may be utilized when desired both when the cover is open or closed.

To close the hatch cover, the control valve 80 is reversed so that the sprocket wheels and endless chains 60 move in the opposite direction, thus towing the covers from the storage compartment onto the coaming. Each successive cover 26, 28 and 30 travels along the cam surface 114 and pivots onto the coaming in a manner just the reverse of the opening operation previously described.

65 70 In the closing operation, the link bars act to pull the successive sections up the cammed surface 114 and along the rollers 118 until the forward wheels of the section engage the flat track 14. When the last section 30 reaches the end of its travel, the last movement will be approximately vertically as the rear wheels reach the track 14, and thus the section encloses the opening 22 and is in position for being sealed. When the four sections are 75 located over the hatch opening, the inflatable gasket 110

is inflated to effect the peripheral and lateral sealing of the hatch cover to the coaming.

It should be noted that the motor 76 can be an electric motor if desired, and a suitable control circuit would be used.

When the hatch cover sections are properly stowed as shown in Fig. 3, the section 30 is lowermost with its rear wheels 106 resting on the deck against a chock member 120. The forward wheels 100 are on the slightly raised cam surface 114 so that the section is in horizontal position. The section 28 is located over the section 30 with its rearmost wheels 96 resting on the upper surface of the section 30. Similarly section 26 is located over the section 28 with its rear wheels 98 resting on the upper surface of the section 28. The section 24 is located over the section 26 and is suspended by the T bars 64.

This method of storage results in a storage compartment of particularly small dimensions.

The link bars between adjacent cover sections are free to slide and pivot in the slots provided in the cover sections through their slideable gudgeons, thus permitting the pivotal movement of the adjacent actions.

It will be obvious to those skilled in the art that various changes may be made without departing from the spirit of the invention and therefore the invention is not limited to what is shown in the drawings and described in the specification, but only as indicated in the appended claims.

What is claimed is:

1. A ship's hatch and cover construction for the deck of a ship provided with a stowage space at one end of said hatch, comprising in combination a hatch coaming having longitudinal and lateral sides upstanding from the ship's deck, a track extending along each of the opposite longitudinal sides of the coaming, a cammed track portion attached to said track and located at the one end of the coaming, said cammed track portion being curved downwardly from said track, a plurality of cover sections adapted to assume adjacent positions covering the entire hatch opening, a plurality of wheels on the sides of said cover sections adapted to travel on said tracks and cammed track portions, rigid link bars for pivotally and slidably interconnecting each two adjacent sections and transmitting operating thrusts, horizontally extending slots in the side walls of said cover sections, means connecting each of said link bars at one of its ends to a slot in one of said sections, means connecting the other end of the link bars to a slot in the adjacent section, said means being pivotally and slidably mounted in said slots, and an actuating means connected to said section most remote from said stowage space adapted to move all said sections from the closed position on the coaming to the stowed position at one end of the hatch coaming.

2. A ship's hatch and cover construction in accordance with claim 1 wherein means are provided for storing said hatch cover sections in substantially horizontal position at one end of the hatch coaming, in stacked relationship, the upper surface of the uppermost said section being at substantially the same height as said coaming.

3. A ship's hatch and cover construction in accordance with claim 1 wherein an enclosed storage compartment is located at one end of said hatch coaming, and means for storing said hatch cover sections in said storage compartment in substantially horizontal position in stacked relationship.

4. A ship's hatch and cover construction in accordance with claim 3, wherein means are provided for suspending said uppermost section from the roof of said storage compartment in substantially horizontal position.

5. A ship's hatch and cover construction in accordance with claim 1 wherein said actuating means comprises a pair of sprocket wheels, an endless chain passing over said sprocket wheels, and a motor adapted to rotate said sprocket wheels to cause movement of said chain which

is connected to said section most remote from said storage space.

6. A ship's hatch and cover construction in accordance with claim 1 wherein a sealing gasket is mounted on the trailing edge of said sections between adjacent sections, and an inflatable gasket is mounted on said coaming adjacent to the upper end thereof between said cover sections and said coaming extending around the entire periphery thereof, whereby when the gasket is inflated said cover sections are compressed together against said sealing gaskets and are sealed around their periphery to said coaming.

7. A ship's hatch and cover construction in accordance with claim 6 wherein said wheels are spaced laterally inwardly from the side walls of said cover sections.

8. A ship's hatch and cover construction for the deck of a ship comprising a hatch coaming having longitudinal and lateral sides upstanding from the ship's deck, a track extending along each of the opposite longitudinal sides of the coaming, a cammed track portion attached to said track and located at the one end of the coaming, said cammed track portion being curved downwardly from said track, at least two cover sections adapted to assume adjacent positions covering the entire hatch opening, a plurality of wheels on the sides of said cover sections adapted to travel on said tracks and said cammed track portions, a rigid link bar for pivotally and slidably interconnecting each two adjacent sections, horizontal slots in the side walls of said cover sections, means for slidably and pivotally connecting said link bar at each end to a slot in an adjacent cover section, the slot in said section nearest one end of said coaming extending along a portion of the length of said section nearest the one end of said coaming, and the slot in said section nearest the other end of said coaming extending along a portion of the length of said section nearest the other end of said coaming, and actuating means connected to said section nearest the other end of said coaming adapted to move all said sections from the closed position on said coaming to the stowed position at one end of said coaming.

9. A ship's hatch and cover construction in accordance with claim 8 wherein a plurality of rotatable rollers are located at the junction of said track and said cammed track portion whereby as each said section reaches said cammed track portion and the rear wheels move downwardly thereon, said section is engaged by said rollers about which said section pivots into stowed position.

10. A ship's hatch and cover construction in accordance with claim 8 wherein wedge-shaped bars are provided at one end of the coaming spaced from the end coaming wall above said cammed track portion and at the same height as said sections whereby as each said section moves from the closed position, the upper end of the section engages the wedge bars and is forced downwardly to effect the pivoting movement.

11. A ship's hatch and cover construction in accordance with claim 9 wherein wedge-shaped bars are provided at the storage end of the coaming spaced longitudinally from said rollers and at the same height as said section whereby as the first said section moves from the closed position the upper end of the section engages the wedge bars and is forced downwardly pivoting about said rollers.

12. A ship's hatch and cover construction in accordance with claim 11 wherein T-slots are provided in the upper surface of said section furthest from the storage end of the hatch, and said wedge-shaped bars being T-shaped in cross section whereby when said T-slots contacts said T-shaped wedge bar, the section will travel along said T-bar and be suspended in horizontal position removed from said coaming and over said other sections which have previously been pivoted downwardly into stowed position.

13. A ship's hatch and cover construction for the

deck of a ship comprising a hatch coaming having longitudinal and lateral walls upstanding from the ship's deck, the coaming lateral wall at one end of the hatch being higher than the opposite lateral wall, an enclosed hatch cover storage compartment located adjacent said lateral coaming wall at one end of said hatch, T-bars mounted on the under surface of the roof of said compartment, a hatch cover adapted to cover virtually the entire hatch opening and fitting within said coaming walls, T-slots in the upper surface of at least one section of said hatch cover, said T-slots and said T-bars being in alignment so that when engaged they act to suspend said hatch cover section in horizontal position completely removed from said hatch coaming, means within said hatch for supporting said hatch cover, an inflatable gasket mounted on said coaming adjacent the upper end on the inner side thereof extending around the entire periphery thereof, whereby a continuous seal may be obtained between said cover and said coaming by inflation of said gasket, and

an opening in said lateral coaming wall at one end of the hatch adapted to permit passage of said cover therethrough into said storage compartment when said gasket is deflated.
